UNITED STATES PATENT OFFICE.

CHARLES J. SOLI, OF RACINE, WISCONSIN, ASSIGNOR OF ONE-HALF TO CHARLES A. SOLI, OF RACINE, WISCONSIN.

GLAZING.

1,217,356.

Specification of Letters Patent. Patented Feb. 27, 1917.

Application filed March 6, 1916. Serial No. 82,388.

To all whom it may concern:

Be it known that I, CHARLES J. SOLI, a citizen of the United States, and resident of Racine, in the county of Racine and State of Wisconsin, have invented certain new and useful Improvements in Glazing; and I do hereby declare that the following is a full, clear, and exact description thereof.

The present invention relates to new and useful improvements in means for securing panes of glass in window sashes particularly of the conventional type, and is more particularly directed to the provision of a means adapted for use in lieu of putty and other more or less unsightly securing means to provide for an efficient holding of the glass in a manner compensating for the usual expansion and contraction thereof.

It is in general the object of the present invention to improve the simplicity and increase the efficiency of devices of the above character, and it is more specifically an object to provide a securing means wherein the glass is at all times held under a metallic spring tension, yet in a manner permitting a certain desired yielding to compensate for various conditions met in practice.

A common disadvantage incident to the use of window pane fasteners, and particularly fasteners of metal types is that rain water tends to settle in the glass receiving groove of the lower sash rail, and thus produce a rotting of the rail and of the fastener and it is further an object of the invention to incorporate in a fastener as above described, means for procuring a proper drainage of water from the sash groove to prevent contact of water with the wood of the sash.

With the above and other objects and advantages in view, the invention resides more particularly in the novel combination, arrangement and formation of parts more particularly hereinafter described and particularly pointed out in the appended claim.

In the drawings:

Figure 1 is an elevational view of a lower corner portion of a window sash, showing the improved glass securing means, the lower rail of the sash and the respective securing means associated therewith, being broken away in successive steps to more clearly disclose the structure.

Fig. 2 is a fragmentary perspective view of the lower rail and securing means, the

end of the structure shown being cut in a plane indicated by the line 2-2 of Fig. 1. Referring now more particularly to the accompanying drawings, 5 designates the lower rail and 6 one of the stiles of an ordinary window sash provided each in the inner edge portion of its outer face with the usual glass receiving groove 7.

Seated in the groove of the bottom rail is a bed plate 8, angular in cross section to fit the faces of the groove, and the usual glass pane 9 is seated on this plate, and bears against the inner leg thereof.

The improved pane securing means is disposed in the recess outwardly of the pane 9, and rests on the bed plate 8, and thus the bed plate, which extends to the outer face of the sash and preferably slightly therebeyond, provides for an efficient drainage of water which might possibly leak between the pane securing means and the sash and thus contact of water with that part of the sash which defines the groove 7 is prevented. It is, however, noted that the present novel pane securing means can be as well employed without this drainage bed plate 8.

The novel securing means comprises a plate 10 of preferably resilient metal associated with each recess 7, and bent longitudinally to form a strip U-shaped in cross section, and this strip is disposed in the recess with its side edges abutting the glass and securing screws 11 are passed through the sides of the strip and into the respective sash portion. A filler of felt or other suitable material is disposed within the channel formed by the strip and thus upon drawing the sides of the strip together by clamping action of the screw, the felt is pressed against the glass and an efficient tight joint is had, which is held under tension by the clamping action of the screw, and it is noted that the resiliency of the strip firmly binds the screws against any accidental displacement. The ends of the securing strips are preferably beveled to form a proper joint at the corners of the sash and in the commercial application of the invention these strips may be provided in continuous length with the felt or other filler suitably associated therewith, and these lengths may be cut into sections to fit various sizes of sashes.

From the foregoing it is seen that an exceedingly simple and efficient device has

been provided, and to provide for the insertion of a fresh pane in the sash it is merely necessary to remove the screws 11 and the entire structure may be reassembled without detracting from its efficiency.

I claim:

The combination with a sash member provided with a glass receiving recess, of an angularly bent plate disposed in the recess 10 with its sides lying against the sides thereof, a glass seated on the bent plate and bearing against its inner side, a second plate bent laterally to provide a U-shaped cross section and disposed against the outer side 15 of the first named plate with its side edges

adjacent the glass, a filler means disposed between the sides of the second plate and bearing against the glass and securing means passed through the sides of the second plate and the adjacent side of the first plate and 20 engaged in the sash member.

In testimony that I claim the foregoing I have hereunto set my hand at Racine, in the county of Racine and State of Wisconsin, in the presence of two witnesses.

CHAS. J. SOLI.
